DUMP TRUCK BODY TILTING MECHANISM

Leonard J. Wasinger, Wakeeney, Kans., assignor
to Trego Manufacturing Company, Inc., Wa-
keeney, Kans., a corporation of Kansas

Application March 20, 1950, Serial No. 150,637

4 Claims. (Cl. 298—19)

1

This invention relates to improvements in dump trucks and has reference more particularly to an improved power operated hoist mechanism for tilting the dump body.

The invention will be described in connection with trucks of the type used for transporting grain, coal, sand, gravel and similar material which will flow along an inclined plane when the angle of tilt is sufficient.

It has long been customary to provide trucks of this type with load carrying bodies pivoted to the rear end of the truck frame and with means for raising the front end of the body to a point where the material will flow downwardly through the lower end of the body whose end gate has been removed or opened to permit the material to escape.

It is the object of this invention to produce a body tilting mechanism of the power operated cable type which shall be of a simple and substantial construction and which can be manufactured and installed without the use of expensive tools.

A further object is to produce a cable operated mechanism of the type employing a winch drum, having a force multiplying device positioned in the cable between the winch drum and object to be operated.

The above and any other objects that may appear as the description proceeds are attained by means of a construction and an arrangement of parts that will now be described in detail, for which purpose reference will be had to the accompanying drawings, in which:

Figure 1 is a side elevation showing the dump body in elevated position, with parts broken away to better disclose the construction;

Figure 2 is a section taken on line 2—2 of Figure 1;

Figure 3 is a top plan view, partly in section, taken on line 3—3, Figure 1, the down position being indicated by broken lines;

Figure 4 is a side elevation showing the parts in normal down position, portions being broken away to better disclose the construction;

Figure 5 is a side elevation, similar to that shown in Figure 1, and shows a slightly modified construction, with the dump body in raised position;

Figure 6 is a section taken on line 6—6, Figure 5;

Figure 7 is a top plan view, partly in section, taken on line 7—7, Figure 5;

Figure 8 is a side elevation, with parts broken away to better disclose the construction;

2

Figure 9 is a diagrammatic view showing two positions of the embodiment illustrated in Figures 1 to 4; and

Figure 10 is a view similar to that of Figure 9 showing two similar positions of the parts shown in Figures 5 to 8.

Referring now to the drawings, reference numeral 10 designates the two side frame members of a wheel mounted truck frame (the springs, wheels, and engine have not been shown), which are interconnected by suitable cross braces in the usual manner (not shown).

An engine is carried by the front end of the frame and has been indicated by E in Figure 3. Shaft 11 is mounted in bearings 12 and carries a winch drum 13. The trucks on the market are practically all provided with winch drums driven from the engine, and the one shown is intended to represent engine driven winches of any construction.

Sides 10 are provided at their rear ends with bearing brackets 14 which form part of a hinge that cooperates with a similar bearing bracket 15 carried by the dump body. Shaft 16 has, for convenience, been shown serving as a pivot about which the dump body 17 tilts. The dump body has been indicated in a general way and, as shown, comprises spaced channel bars 18 to which bearings 15 are attached.

The elevating or dumping mechanism comprises, in addition to the winch, a shaft 19 whose ends are pivoted in bearings 20. Two lifting arms 21 are rigidly attached as by welding to shaft 19. Arms 21 lie in the same axial plane. A shaft or round bar 22 connects the free ends of the lifting arms and its ends serve as bearings for rollers 23 that are positioned in the channels of sides 18 as shown in Figure 2.

Welded to shaft 19, adjacent arms 21, are arms 24 that are in effect prolongations of arms 21. Anchored to shaft 16 by a link 25 is a pulley block having two pulleys 26 that rotate about pivot 27. Links 28 have their rear ends connected with the pivot 27 and their front ends connected with arms 24 by pivots 29. Links 30 have their lower ends connected to arms 24 by the pivots 29 and extend upwardly and inwardly terminating on opposite sides of pulley 31 to which they are attached by a pivot 32. Two links 33 have their lower ends attached to the upper ends of links 30 by the pivot 32 and their upper ends attached to the lifting arms 21, as shown most clearly in Figure 2. Links 30 and 33 cooperate with arms 21 and 24 to form a stress triangle. One end of cable 34 is attached to pivot 32 by a

U-bar 35 and passes rearwardly, thence downwardly over one of pulleys 26, thence forwardly and up over pulley 31, thence rearwardly and downwardly over the other pulley 26, thence forwardly to winch drum 13.

Let us now assume that the parts are in the position shown in Figure 4 and that the winch drum is operated to wind the cable thereonto. When the tension in the cable is P the force tending to move pivots 27 and 32 toward each other is equal to $3P$. It will be observed that, due to links 28, pulleys 26 and 31 must move in opposite directions or not at all, and this therefore produces a further multiplication of force. If we assume that pulleys 26 rotate on a fixed pivot, that is, with links 28 omitted, then the force acting to turn shaft 19 would be $3P$. With the arrangement shown pivots 27 and 32 approach each other at the same rate, that is, when pivot 32 moves one foot pivot 27 will also move one foot in the opposite direction, and this requires six feet of cable to be wound onto the winch drum. It is evident, therefore, that by the use of links 28 producing an equal and opposite movement of the pivots and pulleys, the rotary force or torque exerted on shaft 19 will be doubled. If we examine Figure 4 carefully it will be observed that the rate at which pivot 27 moves longitudinally varies with its angular position, first increasing to a maximum when it is perpendicular and decreasing from 90 to 180 degrees. The torque exerted on shaft 19 per unit pull in the cables will therefore be a maximum when the lever arm equals the distance from center of shaft 19 to pivot 32.

It is evident that when the parts are in the position shown in Figure 4 the lifting force exerted by rollers 23 per unit torque will be a minimum and that it increases as the dump body rises, approaching a maximum when the parts reach the position shown in Figures 1 and 2. If lines 27-16 and 19-32 were vertical, as shown in Figure 9, at the time lifting arms were in the position shown in Figure 4 the torque exerted on shaft 19 per unit cable tension would be a maximum at the time when the lifting force of arms 21 per unit torque was a minimum and that the torque per unit cable tension would decrease as the lifting force of arms 21 increased. Owing to structural considerations the parts are usually so arranged that the torque per unit tension increases to a maximum and then decreases.

In Figures 5 to 8 somewhat similar results are obtained by a slightly different mechanism which will now be described. The truck frame comprises two parallel channel bars 18a. Near the front of the frame where engine E is located a winch shaft 11 is mounted for rotation in bearings 12 and carries a winch drum 13. Brackets 14 are attached to the frame members 18a near their rear ends and serve as supports for shaft 16 on which bearing blocks 15, that serve as supports for the dump body 17 whose frame comprises two channels 18, is supported.

Shaft 18a has its ends supported by brackets 20a and is made in two parts, each of which terminates in a cross bar 37 whose ends are joined by pivots 38 on each of which a pulley 39 is mounted. Lifting arms 21c have their ends welded to shaft 18a and their outer ends are connected by a bar or shaft 40 on the ends of which rollers 41 are journaled, which travel in the channels of frame members 18 as shown more particularly in Figure 6. Braces 42 connect the outer ends of the lifting arms with cross bars 37. 75

A pulley block 43 is connected with shaft 16 or some other stationary anchor. Cable 34 has one end anchored to drum 13 and the other connected with bar 40 and passes about pulley 43, thence over the upper pulley 39, thence under the lower pulley 39.

Let us now assume that the parts are in the position shown in Figure 8, in which position the tension in that part of cable 34 that extends from pulley 43 to shaft 40 exerts practically no torque tending to rotate shaft 19a and the lifting arms. In this position the tension in the cable tends to turn shaft 19a counterclockwise, the lever arms being the perpendicular distances from the center of shaft 19a to the cables. As the shaft rotates the torque increases, due to the increased lever arms, and at the same time the force exerted by the cable on the ends of the lifting arms is increasingly converted into torque. If cross arms were displaced at an angle of about 90 degrees from the lifting arms as shown in Figure 10 the torque due to the coaction between the cable and pulleys 39 would be a maximum when the torque due to the force exerted by the cable on the lifting arms is a minimum and as the shaft turns the former will decrease while the latter increases. For structural reasons the angular relation of the parts has been selected as shown.

From the above it will be apparent that the body dumping mechanism has been so constructed that the torque applied to the lifting arm shaft is near maximum when the lifting arms are in their least effective position and in which the torque, after reaching its maximum per unit cable tension, decreases while the effectiveness of the lifting arms increases.

Having described the invention, what I claim as new is:

1. In a power operated dump truck of the type having a wheel supported frame, spaced side members, an engine supported by the frame adjacent its front end, an engine operated winch drum, and a dump body pivoted to the rear end of the frame for tilting movement; means for tilting the dump body by power from the engine comprising, a transversely extending shaft positioned between the frame members and mounted for pivotation, said shaft having a lifting arm non-rotatably attached to it at each end, positioned to slideably engage the under side of the lifting body, two crank arms non-rotatably attached to the shaft, one adjacent each end thereof, said arms extending at an angle to the lifting arms, a pulley block connected with the frame near the rear end thereof, another pulley connected with the ends of the crank arms by means of links, a cable having one end connected with the winch drum and the other connected with the shaft at a point spaced from the point of connection with the shaft rearwardly about the pulley connected with the frame, thence forwardly about the pulley connected with the shaft, thence rearwardly about a second pulley on the pulley block, and thence forwardly to the winch drum.

2. In a dump truck of the type having a wheel mounted frame having two spaced frame members, an engine at the front end thereof, a power operated winch adjacent the engine, and a dump body supported on the frame and mounted for pivotation about an axis transverse of the frame; means operated by power from the engine for tilting the dump body, comprising a pivoted torque shaft extending across the frame, with its ends pivoted on the frame members, two lifting

arms having one end non-rotatably connected with the torque shaft, one adjacent each end thereof, said arms extending forwardly when the dump body is in its lowered position, the ends of the lifting arms being positioned to engage the under surface of the dump body and to raise the same, means for turning the torque shaft to move the lifting arms and dump body upwardly, comprising a pulley attached to the torque shaft for rotation about a pivot radially spaced from the axis of said shaft and positioned above the axis thereof, a pulley block pivotally connected with the rear end of the truck frame, the pivot of the pulleys being radially spaced from the pivotal connection, a crank arm non-rotatably connected with the torque shaft extending downwardly therefrom, a link connecting the end of the crank arm with the pivot of the pulleys on the pulley block, whereby the axis of the pulleys on the block and the axis of the pulley on the torque shaft will be constrained to move in opposite directions, and a cable having one end connected with the winch drum and its other end connected with the pivot of the pulley carried by the torque shaft, the cable passing rearwardly from the winch drum, over one of the pulleys on the pivoted pulley block, thence forwardly about the pulley carried by the torque shaft, thence rearwardly and about the other pulley on the pulley block, thence forwardly to its connection with the pulley on the torque shaft.

3. In a dump truck having a wheel mounted frame with spaced parallel side members, an engine and an engine driven winch drum at the front end and a dump body pivoted adjacent its rear end to the rear end of the frame, means for 35 tilting the dump body comprising a shaft extending across the frame at a point between the ends

of the dump body, at least one pulley connected with the frame body, two radially extending lifting arms rigidly connected with the shaft, one adjacent each side member, the free ends of the arms slidably engaging the underside of the dump body at a point forward of the shaft, means for turning the shaft and lifting arms in a direction to raise the front ends of the arms, said means comprising a pulley attached to the rear end of the frame, crank arms rigidly attached to the shaft, a pulley operatively attached to the ends of the crank arms and positioned above the shaft, a cable encircling the pulleys, one end of the cable being attached to a pulley mounting, the other end being attached to the winch drum whereby the two pulleys will move towards each other when the cable is wound onto the winch drum thereby turning the shaft in a direction to raise the ends of the lifting arms.

4. A device in accordance with claim 3 in which the force multiplying device comprises two pulleys positioned on opposite sides of the shaft, the cable passing over said pulleys, the bights of the cable facing a diametrical plane, the angles of the bights being minimum when the dump body is horizontal.
